INVENTOR
JAMES STOCKLEY.

BY Peterstone ¹⁸⁷¹ ~~1870~~

UNITED STATES PATENT OFFICE.

JAMES STOCKLEY, OF HALIFAX, NOVA SCOTIA, CANADA.

CONCRETE MIXER.

1,421,320.

Specification of Letters Patent. Patented June 27, 1922.

Application filed August 8, 1921. Serial No. 490,687.

To all whom it may concern:

Be it known that I, JAMES STOCKLEY, a subject of the King of Great Britain, and resident of the city of Halifax, in the Province of Nova Scotia, Dominion of Canada, have invented certain new and useful Improvements in Concrete Mixers, of which the following is a specification.

This invention relates to concrete mixers and has for its objects to provide a device whereby concrete may be mixed mechanically, to provide a means whereby the pan containing the stone, cement and sand will be rocked, to provide means whereby suitably inclined blades will be rotated in the pan, to provide means whereby the pan may be brought in an inclined position in order to be discharged by its contents.

These objects are attained by means of a pan supported on an axle and designed to be rocked on its base, the pan also carrying an upright shaft engaging a hub carrying plates which are adapted to be rotated within the pan.

Further objects are to provide a concrete mixer that is simple in construction and not liable to go out of repair and generally to adapt the several parts to better perform the functions required of them.

With the above and other objects in view, the invention consists essentially of the improved construction hereinafter described in detail in the accompanying specification and drawings.

In the drawings:—

Figure 1 is a front elevation of the improved concrete mixer.

Figure 2 is a plan view of the same.

Figure 3 is a vertical section.

Figure 4 is a plan view of the blades.

Figure 5 is an elevation of the same.

Figure 6 is a cross section taken through an alternative form of blade.

Figure 7 is a vertical section of the improved mixer showing an alternative form of blades.

Figure 8 is a side elevation of the alternative form of blades and post.

Figure 9 is a plan view of the same.

Figure 10 is a vertical section of the post used in the alternative form shown in Figure 8.

Figure 11 is a front elevation of the bolt connecting the blades to the axle.

With the above and other objects in view,

the invention consists essentially of the improved construction hereinafter described in detail in the accompanying specification and drawings.

Referring to the drawings, A represents the improved concrete mixer, comprising a base 10 formed with two side members 11 and 12 both tapering outwardly and downwardly and formed in the middle part thereof with bearings in which are journalled two circular ends 13 and 14 of a square axle 15.

On the square axle 15 is provided a pan 16 circular in form and rigidly connected to the axle by means of the bent arms 17 engaging the top of the pan and having a threaded end extending through the circular ends 13 and 14 of the axle and rigidly held therein by means of the nuts and washers 18 in threaded engagement with the threaded end of the arms 17.

In the centre of the pan 16 is provided an upright shaft 19 extending through the axle 15 and rigidly kept in position by means of two wedges 20 and 21 located beneath the axle 15.

A hub 22 engages the upright shaft 19 and is held against any vertical movement by means of an annular rib 23 formed on the upright shaft 19.

The rib 23 can be replaced if desired by means of a pin extending through the upright shaft 19 and designed to hold the hub 22 from any vertical movement.

The hub 22 is formed with side inclined ears 24 and 25 engaging opposite inclined blades 26 and 27 equal in length to the diameter of the pan 16 and adapted to be rotated therein in order to completely mix the cement.

The hub is provided on either sides thereof with two plates 28 and 29 each formed with extensions having an intervening notch 30. The notches 30 are engaged by a transversely extending arm 31 formed with handles 32 which is designed to rotate the plates within the pan. The arm 31 may also be used to rock the pan 16 on its base.

The extensions 28 and 29 could also be made integral with the hub 22 by being cast in single piece therewith thereby forming a head as shown in Figure 5 of the drawings.

If wooden blades are used the same will be triangular in cross section as shown in Figure 6 of the drawings and the ears 24 and 25

25 designed to carry the blades will merely have to be slightly changed in form in order to carry these wooden plates 33.

The pan 16 is formed with a side opening 34 which registers with a chute 35 provided on the side of the pan and through which the contents of the pan are to be discharged when the same is brought in the inclined position as shown in dotted lines in 10 Figure 3 of the drawings.

The opening 34 in the pan 16 is designed to be closed by means of a sliding door 36 which is designed to be operated by a lever 37 connected thereto and fulcrumed at 15 38 on the side of the pan 16.

When this concrete mixer is in use, the sand, stone and cement are placed in the pan in the required quantity and the blades 26 and 27 are rotated in the pan 16 by means 20 of the arm 31 which may be manipulated by two men gripping the notches 32 at each end thereof.

To get a thorough mixing of the concrete, when this rotating movement is finished 25 the pan 16 may be rocked on its axle 15 also by means of the arm 31 room being allowed for the rocking movement through the side members 11 and 12 being tapered outwardly and downwardly as previously described.

30 When the concrete is to be taken from the pan 16 the door 36 is opened by means of the lever 37 and the pan 16 brought in inclined position shown in Figure 3 of the drawings so that the concrete may be discharged through the chute 35.

It is obvious that the blades 26 and 27 may be made of any suitable form and of any material although if made of wood, the form shown in Figure 6 of the drawings 40 is that which is best adapted as the cement same has more strength than other forms.

The hub 22 and plates 28 and 29 may also be of separate members connected together by means of bolts or rivets, but it 45 is also obvious that the same can be cast together thus forming one integral structure as shown in Figure 5 of the drawings.

An alternative form of blade that could also readily be used in the mixer is shown 50 in Figs. 7 to 11 inclusive.

In this instance the pan 16 is secured to its axle 15 by means of the bolt and nut 40. The head of the bolt 40 is formed like a plain shank 41 designed to be housed with- 55 in a longitudinal recess 42 provided in an upright member 43 to which member a pair of angle-iron blades 44 are secured in angular relation by means of brackets 45. The top part of the upright member 43 is pro- 60 vided with a notch 46 designed to engage the transverse arm 31 operating the mixer.

Several styles of blades have been described but it is desired to have it understood that any special make of blades could be used with this mixer although the blades 65 described are the preferred forms for having been tested.

As many changes could be made in the above construction and many apparently widely different embodiments of my invention, within the scope of the claims constructed without departing from the spirit or scope thereof, it is intended that all matter contained in the accompanying specification and claims shall be interpreted as illustrative and not in a limiting sense.

What I claim as my invention is:

1. A concrete mixer comprising a base formed with bearing blocks, a square axle formed with circular ends journalled in the 80 bearings, a pan rigidly mounted on the axle, an upright shaft mounted in the pan, a hub on the shaft formed with oppositely inclined pairs of ears, blades carried by the ears, plates on the hub having notched ex- 85 tensions and an arm located in the notches, adapted to rotate the blades and rock the pan.

2. A concrete mixer comprising a base, formed with bearing blocks, a square axle 90 having two circular ends, journalled in the bearings, a pan rigidly mounted on the axle, an upright shaft in the pan extending through the axle and formed with an annular rib, a hub on the shaft engaged by the 95 annular rib, and carrying oppositely inclined pairs of ears, blades carried by the inclined ears, a notched head on the hub, and an arm located in said notched head and adapted to rotate the blades.

3. A concrete mixer comprising a base, formed with bearing blocks, a square axle having two circular ends journalled in the bearings, a pan rigidly mounted on the axle, a chute formed on the pan, a door slidably mounted in the chute, a lever fulcrumed on the pan adapted to operate the door, an upright shaft in the pan extending through the axle, and formed with an annular rib, a hub on the shaft engaged by the rib and 110 formed with oppositely inclined pairs of ears, blades extending in diametrically opposite directions and carried by the inclined pairs of ears, a notched head on the hub, and an arm located in said notched 115 head and adapted to rotate the blades.

In witness whereof I have hereunto set my hand in the presence of two witnesses.

JAMES STOCKLEY.
